ORE REDUCTION APPARATUS

Harry G. Twiford, Los Angeles, Calif.

Application March 27, 1942, Serial No. 436,504

2 Claims. (Cl. 266—33)

My invention relates to improvements in ore reduction apparatus for use in recovering metals and other properties from ore.

The invention is designed with the principal object in view of providing efficient, simply constructed and easily controlled apparatus for feeding under pressure fine particles of ore and flux directly to heat at a temperature sufficient to bring the particles immediately to a melting point, thereby obviating any mass accumulation.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of my improved apparatus in its preferred embodiment, and

Figure 2 is a view in vertical central section of the furnace.

Referring to the drawings by numerals, my improved apparatus comprises, as its basic component, a furnace 1 including an inner cylindrical, open-top wall 2 forming an inner combustion chamber 3, and an outer wall 4 and dome 5 forming a circular, outer combustion chamber 6 around the wall 2 and chamber 3 with a top 7 arching over the top of the inner chamber 3. The chamber 3 is provided with a downwardly tapering, substantially conical, bottom well 8 opening into one end of a lateral passage 9 which at its other end communicates with a vertical passage 10. An annular, internal baffle forming ledge 3' extends around the chamber 3 at its juncture with the well 8.

At the juncture of the passages 9, 10 is a slag discharge outlet duct 11 inclining downwardly from the bottom of the passage 9. Contiguous to and spaced inwardly from said duct 11 is a small, metal collecting sump 12 in the bottom of the passage 9 having a downwardly and outwardly inclined metal discharge duct 12' leading from the bottom thereof.

On the side of the furnace opposite the passage 10, a lateral opening 13 is provided in the outer wall of the furnace for supplying heat to the bottom of the outer combustion chamber 6. A similar opening 14 is provided beneath the opening 13 for introducing heat into the inner combustion chamber 3 at the juncture thereof with the bottom well 8.

It is contemplated that heat be introduced

through the openings 13, 14 by means of any suitable injector-type gas or oil burners, such as shown, for example, in Figure 2 and designated 13', 14', respectively.

Above and to one side of the furnace 1 is a closed ore supply tank 15 for receiving finely divided ore introduced therein by way of a hopper 16 surmounting the tank with a suitable control valve 17 at the bottom thereof. A pressure gauge 18 is provided on top of the ore supply tank 15 for a purpose presently seen.

Beneath the ore supply tank 15 is a pressure storage tank 19 for air communicating with the bottom of the ore supply tank 15 adjacent one side of the latter by means of a pipe 20 having a suitable control valve 21 interposed therein. A nipple 22 at the bottom of the pressure storage tank 19 is provided for suitable connection to an air compressor, not shown.

Extending from the opposite side of the ore supply tank 15 is a lateral ore supply pipe 24 having a suitable control valve 25 interposed therein, said pipe opening into a vertical branch pipe 26 extending downwardly through the top of the furnace 1 axially of the inner combustion chamber 3 into the top of the latter.

An emergency pressure release valve 27 is provided in the upper end of the branch pipe 26.

The passage 10 opens adjacent its upper end into a laterally extending branch 27' of a gas condensing unit, said pipe having a downturned branch 28 extending into a condensation tank 29.

A trap 30 for condensates, or precipitates, is interposed in the branch 27'.

An emergency safety valve 31 for pressure relief is provided at the top of the passage 10.

Referring now to the operation and use of the described apparatus, with the valves 21, 25 closed and the valve 17 open, the ore supply tank 15 is filled with finely divided ore to the desired level. The valve 17 is then closed and the valve 21 opened to introduce compressed air from the compressed air storage tank 19 into the ore supply tank 15 until the pressure is built up therein, as indicated by the pressure gauge 18, well above the pressure existing in the furnace 1. The valve 25 is then opened, whereupon, the finely divided ore is ejected under pressure from the ore supply tank 15 and through pipes 24, 26 into the inner combustion chamber 3. The air introduced with the ore into the furnace facilitates combustion, as will be clear. It will be understood that the temperature in the furnace 1, that is, in the chambers 3 and 6, has been raised to bring the ore introduced therein to

55

the melting point. The heat introduced into the outer combustion chamber 6 rises and curves over the top of the wall 2 down into the combustion chamber 3 and along with the heat supplied to the latter passes downwardly along the inner wall of said chamber 3 and of the well 8 into the passage 9 and up the passage 10 into the described condenser. The trap 30 eliminates the condensates or precipitates.

As will be seen, the ore is caused under a downward flow of air to also float downwardly into the inner chamber 3, or center of the furnace, with the air to the passage 9 and the fine ore follows the hot wall of the chamber 3 and is immediately melted thereon. At the baffle ledge 3' the melted ore is slightly retarded in its downward flow and subjected at the top of the well 8, particularly, to added heat and then flows down the wall of the well 8 to the passage 9. As it travels through the passage 9 the melted metal settles in the sump 12 and discharges therefrom by way of the port 12', while the slag passes out of the discharge port 11. The wall 2, as will be seen, is heated on both sides and thereby provides a centralized hot zone into which the ore is directly delivered to facilitate melting.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the subjoined claims.

What I claim is:

1. Ore reduction apparatus comprising a furnace including a centralized solid inner cylindrical wall forming an inner open top circular combustion chamber, a downwardly tapering well at the bottom of said chamber into which the latter opens directly, an outer side and top forming wall spaced from said inner wall and the top

of the inner chamber and forming an annular outer combustion chamber surrounding said inner wall and inner chamber from top to bottom thereof and communicating at its top with said

5 inner chamber, lateral apertures in said outer wall communicating with the bottoms of said inner and outer chambers, respectively, for containing burners, a lateral discharge passage for molten metal in said furnace leading from the bottom of said well to the outside atmosphere, means to feed finely divided ore under pressure downwardly through the top of the outer wall into the top of the inner chamber, a condenser for the gases passing through said lateral discharge passage, and a vertical passage leading from said lateral discharge passage adjacent the outer end thereof to said condenser.

2. Ore reduction apparatus comprising a furnace including a centralized solid inner cylindrical wall forming an inner open top circular combustion chamber, a downwardly tapering well at the bottom of said chamber into which the latter opens directly, an outer side and top forming wall spaced from said inner wall and the top of the inner chamber and forming an annular outer combustion chamber surrounding said inner wall and inner chamber from top to bottom thereof and communicating at its top with said inner

25 chamber, lateral apertures in said outer wall communicating with the bottoms of said inner and outer chambers, respectively, for containing burners, a lateral discharge passage for molten metal in said furnace leading from the bottom of said well to the outside atmosphere, means to feed finely divided ore under pressure downwardly through the top of the outer wall into the top of the inner chamber, and a sump under said lateral discharge passage adjacent the outer end and having a discharge duct extending therefrom through said outer wall.

30 3. Ore reduction apparatus comprising a furnace including a centralized solid inner cylindrical wall forming an inner open top circular combustion chamber, a downwardly tapering well at the bottom of said chamber into which the latter opens directly, an outer side and top forming wall spaced from said inner wall and the top

35 of the inner chamber and forming an annular outer combustion chamber surrounding said inner wall and inner chamber from top to bottom thereof and communicating at its top with said inner

40 chamber, lateral apertures in said outer wall communicating with the bottoms of said inner and outer chambers, respectively, for containing burners, a lateral discharge passage for molten metal in said furnace leading from the bottom of said well to the outside atmosphere, means to feed finely divided ore under pressure downwardly through the top of the outer wall into the top of the inner chamber, and a sump under said lateral discharge passage adjacent the outer end and having a discharge duct extending therefrom through said outer wall.

HARRY G. TWIFORD.
